UNITED STATES PATENT OFFICE.

WILLIAM JACKSON BURNETT, OF THOMASVILLE, GEORGIA.

PLOW.

Application filed August 16, 1922. Serial No. 582,198.

To all whom it may concern:

Be it known that I, WILLIAM JACKSON BURNETT, a citizen of the United States, residing at Thomasville, in the county of Thomas and State of Georgia, have invented a new and useful Plow, of which the following is a specification.

This invention relates to plows of that type known as "middle breakers" or "middle bursters," one of the objects of the invention being to provide a novel assembly of a point, wing and sweep adjustably and detachably connected whereby the plow can be operated either for cleaning out a furrow or for subsoiling.

Another object is to provide simple and efficient means for holding the parts together and assembled with the standard.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a front elevation of the plow, the beam being broken away.

Figure 2 is a side elevation, the beam being broken away.

Figure 3 is a perspective view of the point.

Figure 4 is a perspective view of the wing.

Figure 5 is a perspective view of the connecting stem.

Figure 6 is a front elevation of the plow, showing the parts adjusted for subsoiling.

Referring to the figures by characters of reference 1 designates a portion of a plow beam to which is connected an elongated loop 2 forming the standard of the plow. To the lower end of this standard may be connected a runner 3 having sweeps 4 secured to the sides thereof and diverging rearwardly. The construction and mounting of the sweeps and runner does not in itself constitute any part of the present in-

vention and, therefore, it is not deemed necessary to describe or show the same in detail.

Straddling the standard 2 is a transversely bowed stem 5 having an elongated slot 6 therein. From the lower end of this stem projects a pointed backing plate 7 having openings 8 therein.

A point, one form of which has been illustrated in Figure 3, is adapted to be placed upon the backing plate 7, this point, which has been designated by the numeral 9, being formed with a central longitudinal ridge 10 and with rearwardly diverging extensions 11 the lower edges of which are adapted to scrape along the ground as shown at 12. 70 Bolts 13 are extended through openings 14 in the upper portion of the point and are secured within the openings 8 in plate 7.

A wing plate 15 is adapted to be placed upon the stem 5 and is so shaped at its lower end as to fit snugly against the middle portion of the upper edge of the point 9. This plate has upwardly diverging wings 16 and a central longitudinal slot 17. Slot 17 receives a king bolt 18 which is extended through the slot 6 and between the sides of the standard 2 and is engaged by a nut 19 which, when tightened, serves to bind the several parts together securely.

When the wing plate 15 is set up against the point 9 and the parts securely fastened, as shown in Figures 1 and 2, the plow is ready for use to clear out furrows. When it is desired to use the plow for subsoiling the bolt 18 is loosened and the stem 5 adjusted downwardly so as to support the point 9 below and spaced from the lower end of the wing plate 15. By then tightening the bolt 18 the parts will be held against relative movement. (See Figure 6.)

It is to be understood that points of different shapes and sizes can be used and that different kinds of wing plates can also be employed.

What is claimed is:—

In a plow the combination with an elongated loop constituting a standard, of a backing plate, a longitudinally channeled slotted stem integral with the backing plate and straddling the standard, a point detachably secured to the backing plate and having its upper edge outstanding from the stem to constitute an abutment, a wing plate

bearing against the slotted stem and abutting the edge of the point, the front faces of the point and plate being flush at their meeting edges, said wing plate being slotted, and means extending through the wing plate, stem and standard for holding them together adjustably.

In testimony that I claim the foregoing as my own, I have hereto affixed my signature in the presence of two witnesses.

WILLIAM JACKSON BURNETT.

Witnesses:

B. F. COOPER,
E. B. STEPHENSON.
